US0D1079625S

(12) **United States Design Patent** (10) **Patent No.:** **US D1,079,625 S**
(45) **Date of Patent:** **** Jun. 17, 2025**

(54) **WIRELESS CHARGER**

- (71) Applicant: **Longconn Electronics (Shenzhen) Co., Ltd.**, Shenzhen (CN)
(72) Inventor: **Lijun Wei**, Shenzhen (CN)
(73) Assignee: **Longconn Electronics (Shenzhen) Co., Ltd.**, Shenzhen (CN)

(**) Term: **15 Years**

(21) Appl. No.: **29/906,343**

(22) Filed: **Nov. 3, 2023**

(30) **Foreign Application Priority Data**

- Oct. 20, 2023 (CN) 202330680530.5
(51) LOC (15) Cl. 13-02

(57) **CLAIM**

The ornamental design for a wireless charger, as shown and described.

DESCRIPTION

FIG. 1 is a front, right and top perspective view of a wireless charger, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right and top perspective view of a wireless charger in unfolded state;

FIG. 10 is a rear, left and bottom perspective view of a wireless charger in unfolded state; and,

FIG. 11 is an enlarged view of portion 11 of FIG. 1 thereof. The broken lines shown in the drawings illustrate portions of the wireless charger that form no part of the claimed design. The dot-dash broken lines depict the boundaries of the enlargements that form no part of the claimed design.

1 Claim, 11 Drawing Sheets
